UNITED STATES PATENT OFFICE.

MILTON O. THOMPSON, OF BOSTON, MASSACHUSETTS, ASSIGNOR TO THE AIR TOY COMPANY, OF BERLIN, MASSACHUSETTS.

AERIAL TOY.

Application filed April 2, 1924. Serial No. 703,721.

To all whom it may concern:

Be it known that I, MILTON O. THOMPSON, a citizen of the United States, residing at Boston, county of Suffolk, State of Massachusetts, have invented a certain new and useful Improvement in Aerial Toys, of which the following is a specification, reference being had therein to the accompanying drawings.

10 The invention relates to a new and useful improvement in aerial toys.

The object of the invention is to provide a simple, inexpensive aerial toy which may be easily operated by a child.

15 The invention will be fully understood from the following description when taken in connection with the accompanying drawings, and the novel features thereof will be pointed out and clearly defined in the 20 claims at the close of the specification.

In the drawings:

Fig. 1 is a plan view of a device embodying the invention.

25 Fig. 2 is a front elevation of a device embodying the invention, showing, in dotted lines, the position of the fingers in operating it.

Fig. 3 is a side elevation.

30 Fig. 4 is a front elevation of the guide member detached.

Fig. 5 is a side elevation of the guide member.

Fig. 6 is an end elevation of the guide member.

35 Fig. 7 is a front elevation of a modified form of guide.

Fig. 8 is an end view of Fig. 7.

Fig. 9 is a section on line 9—9 of Fig. 2.

40 Referring now to the drawings: There is shown at A a top member fashioned somewhat after the manner of two propeller blades whose axes are in the same straight line and rigidly connected together having a middle head portion 1 which is relatively thick and two oppositely disposed wings 2, 3. The top member A is mounted fast on the upper end of a spindle B which projects from the middle of the lower face of the said head portion and extends at 45 right angles to the lower face of the said head portion 1. The device when assembled is T-shaped as shown in Fig. 2. The parts should all be made of some material of light

specific gravity, preferably wood, but it may be of some light metal or other suitable material.

The head 1 is preferably thicker than the wings but even this should be as thin as possible consistent with strength and rigidity. For instance, if the top member A is 60 ten or twelve inches in length, the head portion 1 should preferably be about one-quarter of an inch thick and about one inch wide. Preferably also the spindle B should be a little longer than the top member A. 65 The exact proportions, however, are not essential. In operation the device should be held with the head member uppermost, preferably with the spindle in vertical position, or slightly inclined to the vertical so that 70 the axis of the top member will be horizontal or nearly so. The longitudinal axis of the top A through the head 1 and the two wings is at right angles to the axis of the spindle and, therefore, horizontal when 75 the spindle is in a vertical position. When so held the faces of the wings are slightly inclined to the horizontal from the rear edge to the advance edge, as shown in Figs. 2 and 3. Both the upper and lower faces of 80 the head portion 1 will be horizontal. As the two wings are diametrically opposite each other when viewed in front elevation one wing will pitch downward and the other will pitch upward.

85 In operating the device the spindle should preferably be rotated counter-clockwise unless the device is constructed for use by a left-handed person. When constructed for rotation counter-clockwise the left-hand wing 3 should be inclined downward transversely from front to rear, as viewed in Figs. 2 and 9, and the right-hand wing 2 should be inclined upward from front to rear, when so viewed, (see Fig. 3) that is, 90 the two wings should have their faces oppositely inclined and in such manner that the higher edge of each wing is the advance edge and cuts the air during the rotation, otherwise the device will not rise. 100

The exact angle or pitch or inclination of the faces of the wings is not material but it should be very slight, both wings being pitched at an equal angle to a plane which is perpendicular to the axis of the spindle 105 but in opposite directions to each other, so

that when viewed from the same position one of the wings is upwardly inclined while the other is downwardly inclined.

Preferably each wing should be flat on its under face 21 and 31 respectively and slightly crowned or convex on the upper face 22 and 32, respectively, as shown in Figs. 3 and 9. This gives a relatively thin edge which enables the wings to cut the air with less resistance than if it were of uniform thickness transversely. The crowned upper face also lessens the resistance of the air during the ascent of the device. The under face should be flat as it affords greater sustaining power to resist falling by gravity.

The spindle B is provided with means for rotating it by means of a string or the like, as shown at 4. Preferably this string 20 is detachably connected with the spindle somewhat above the middle of its length but this is not essential. The spindle is shown as provided with a transverse hole 10 through which the end of the string is 25 loosely threaded to keep the string from slipping during the winding and unwinding, the string then being wound about the spindle, as shown in Fig. 2. The outer end of the string is provided with suitable 30 means for a finger hold. Preferably a short stick 5 is employed but any other suitable finger grip may be used. After one end of the string is threaded through the hole, it being merely just passed through the hole, 35 the other part of the string is wound around the spindle as shown in Figs. 2 and 3 preparatory to rotating the spindle to operate the device as already described, the winding being counter-clockwise.

40 A guide member is provided to support and guide the string and to enable the operator to properly hold the device during the rotation. The preferred form of guide is a semi-tubular shell, as shown at 6, the inner 45 diameter of the guide being slightly larger than the diameter of the spindle so that the concave face will partially embrace the spindle and the coil of string, as shown in Figs. 2 and 3.

50 The guide 6 is formed with a thin slot 7 extending from one side edge of the guide transversely inward for some distance, the slot being of a width to easily receive the string. The guide should be positioned on 55 the spindle with the concave face of the guide embracing the spindle and coiled string and with the slot engaging the uncoiled portion of the string. The guide and the spindle may be grasped between the 60 thumb and one of the fingers of the left hand, as shown in dotted lines, in Fig. 2. The pull handle 5 on the outer end of the string may be held by two of the fingers of the right hand, the string passing between 65 the fingers, as shown in Fig. 2. The spindle

and guide member should be held lightly but steadily by the left hand so that the spindle may easily rotate when the string is pulled by the right hand and quickly unwound from the spindle thus furnishing 70 the power to rotate the spindle and the wings mounted thereon together. Just before the string is entirely unwound the guide member should be quickly snatched away by the hand which holds it, leaving the spindle 75 free. As the inner end of the string is just loosely inserted through the hole in the spindle, it will slip out again when the string is all unwound, leaving it free from the spindle. On account of the inclined 80 faces of the wings, the rotation of the wings and of the spindle on the axis of the spindle will cause the spindle and the wings to fly upward until the rotation of the spindle and wings slow down when the device will begin to drop. If the spindle is held in a vertical position when it is rotated, it will 85 begin its ascent in a vertical direction. By holding the spindle at a slight angle to the vertical when it is rotated, the flight will 90 at first be in the same direction as the angle at which the spindle is headed.

Of course, the size and weight of the device and number of windings of the string and skill in manipulation will all effect the 95 duration of the flight.

Instead of making the guide semi-tubular as described, it may be made tubular, as shown at 8 in Figs. 7 and 8. In such case, it will be formed with a slot 9 extending 100 transversely inward to receive the string. When it is made tubular, the spindle will have to rise out of the guide member or the guide member will have to be pulled directly down in order to release the spindle 105 from the guide, whereas in the semi-tubular form previously described, the guide member may be pulled away laterally.

The spindle being fast to the top member, goes with it in its flight and stabilizes 110 the device.

What I claim is:

1. An aerial toy comprising a head member having two oppositely extending wings connected therewith, a spindle connected with the head and extending from the under face of the head at right angles thereto, in combination with a separable guide member having one side formed with a longitudinal groove throughout its length to receive the spindle, said guide being formed with a thin transverse slot extending from one side edge of the guide inwardly to intersect said groove and adapted to releasably engage a string wound around the spindle, said slot being open at its outer end.

2. An aerial toy comprising a head member having two oppositely extending wings, a spindle connected with the head and ex-

tending at right angles thereto, in combination with a separable, semi-tubular guide member having one side concave in transverse section throughout its length, the 5 groove formed by the concave face being adapted to loosely receive the spindle in the axial direction thereof, said guide being formed with a thin transverse slot extending from one side edge inwardly to intersect said groove, a string having one end portion adapted to be wound around said spindle, the other end being free while the intermediate portion engages said slot, the 10 inner end of the string being releasable

from the spindle as soon as the string is 15 unwound, said guide member being adapted to be held by the hand to maintain the string in the slot during the unwinding and being at all times releasable at will from the spindle and from the string in a lateral 20 direction, the winding of said string around the spindle and its releasable engagement with said slot being the only connection between the spindle and the guide.

In testimony whereof I affix my signature. 25

MILTON O. THOMPSON.
